DESIGN FOR A PHOTOGRAPHIC FRAME RACK OR SIMILAR ARTICLE

Joseph Worth, New York, N. Y.

Application July 24, 1944, Serial No. 114,541

Term of patent 14 years

(Cl. D61—1)

To all whom it may concern:

Be it known that Joseph Worth, a citizen of United States and resident of New York, in the county of Queens and State of New York, has invented a new, original, and ornamental Design for a Photographic Frame Rack or Similar Article, of which the following is a specification, reference being had to the accompanying drawing, forming part thereof, and in which,

Fig. 1 is a side elevational view of the photographic frame rack, embodying my new design; and

Fig. 2 is a top plan view thereof; while Fig. 3 is an end view of the same.

I claim:

The ornamental design for a photographic frame rack or similar article, substantially as shown.

JOSEPH WORTH.
